UNITED STATES PATENT OFFICE.

BERTIE L. BAILEY, OF GRESSTON, GEORGIA.

KITCHEN-RACK.

No. 888,295.

Specification of Letters Patent.

Patented May 19, 1908.

Application filed October 22, 1907. Serial No. 398,698.

To all whom it may concern:

Be it known that I, BERTIE L. BAILEY, a citizen of the United States, residing at Gresston, in the county of Dodge and State of Georgia, have invented new and useful Improvements in Kitchen-Racks, of which the following is a specification.

This invention relates to kitchen racks, the object of the invention being to provide a 10 cheap and convenient rack for use in kitchens, the same being adapted for the support of spoons, forks, dish cloths and various other articles and being further especially adapted for drying dish cloths and the like.

15 With the above and other objects in view, the invention consists in the novel construction, combination and arrangement of parts hereinafter fully described, illustrated and claimed.

20 In the accompanying drawings, Figure 1 is a front elevation of the kitchen rack embodying the present invention. Fig. 2 is an end view thereof. Fig. 3 is an enlarged detail perspective view of one of the pivotally 25 mounted clothes pins.

The rack of this invention is composed throughout of wire which may be galvanized to prevent rust. In the construction of the rack, several lengths of wire of suitable gage 30 are bent and twisted together so as to form when completed a series of horizontal bars 1, 2, 3 and 4, and another series of vertical bars 5, 6, 7 and 8, and in this connection, it is to be noted that the number of horizontal and vertical bars may be increased or diminished to 35 satisfy the taste of the manufacturer. The top bar is provided at one or more points with suspending eyes or hooks 9 by means of which the rack as a whole may be hung on a 40 wall, partition or similar support. The remaining horizontal bars are fashioned into hooks 10 adapted for the support of spoons, forks, dish cloths and the like. On account of these hooks being interposed between the 45 vertical bars, any strain on the hooks will be distributed by means of the vertical and horizontal bars to different parts of the rack.

In the manufacture of the main body of the rack, the vertical end wires 5 and 8 are 50 connected at their upper and lower extremities by the top and bottom horizontal wires as clearly shown in Fig. 1 and also by the central intermediate wire 3. The other intermediate vertical wires are then connected 55 with the top and bottom and central intermediate horizontal wires after which the

other intermediate horizontal wires 2 and 4 are connected with all of the vertical wires. The horizontal wires are wrapped around the vertical wires and made up of sections, the 60 adjoining ends of which are twisted together to form hooks at the same time producing a tension on both the horizontal and vertical wires and thereby making a strong and practically indestructible rack frame. 65

In connection with one or both end bars of the rack, I employ one or more pivoted and folding arms 10' having upturned extremities or hooks 11 upon which cloths may be mounted to be dried. On each of the pivoted and 70 folding drier arms 10' is mounted one or more clothes pins 12, each of which is formed as shown in Fig. 3 of a single length of wire, the middle portion of which is fashioned into the shape of the letter "E" to form a clamp 75 for holding the cloth while the ends of the wire are coiled around the body of the drier arm 10' so as to anchor the clothes pin securely thereto while adapting said clothes pin to be turned upon said arm to bring the 80 clamping portion of the clothes pin either above or below or to either side of the drier arm, as may be desired. By thus fastening the wet cloths upon the drier arms they are prevented from being blown away. When 85 the arms 10' are not in use, they may be folded closely against the body of the rack for transportation or storage.

The arms 10' are of a size adapting them to be swung inward into the spaces or openings 90 between the meshes of the vertical and horizontal wires so that when said arms 10' are folded inward they are contained within the plane of the rack and are entirely out of the way so as not to interfere with suspending 95 various articles on the hooks 10. Likewise, the clothes pins 12 which are journaled on the drier arms 10' are adapted to be swung into the plane of the arms so that when the arms are folded inwardly said pins will lie in 100 the plane of the body of the rack. Thus, when the arms and pins carried thereby are folded into the openings adjacent thereto, they will not interfere with hanging articles on the hooks 10. 105

Having thus fully described the invention, what is claimed as new is:—

A rack for the purpose set forth embodying a frame comprising vertical end wires, top and bottom and intermediate horizontal 110 wires connecting the end wires and each composed of sections, the adjoining ends of which

are twisted together to form hooks, intermediate vertical wires connecting the horizontal wires and leaving openings between the vertical and horizontal wires, one or more drier arms journaled on the vertical end wires and adapted to fold into the adjacent opening or openings, and one or more clothes pins journaled on each arm and adapted to be

turned so as to lie in the opening or openings and within the plane of the rack. 10

In testimony whereof I affix my signature in presence of two witnesses.

BERTIE L. BAILEY.
